JOHN ALLEN HEANY, OF NEW HAVEN, CONNECTICUT, ASSIGNOR, BY MESNE ASSIGNMENTS, TO ROCKBESTOS PRODUCTS CORPORATION, A CORPORATION OF DELAWARE.

INSULATING FLAT-WIRE CONDUCTORS.

1,426,065.

Specification of Letters Patent. Patented Aug. 15, 1922.

Application filed November 16, 1918. Serial No. 262,873.

To all whom it may concern:

Be it known that I, JOHN ALLEN HEANY, a citizen of the United States of America, residing at New Haven, in the county of New Haven and State of Connecticut, have invented certain new and useful Improvements in Insulating Flat-Wire Conductors, of which the following is a specification.

This invention relates to insulated conductors and to a means and method for applying insulating material to conductors of the flat-wire type, and is a modification of the inventions shown in my Patents Nos. 1,071,676, dated Aug. 26, 1913, and 1,155,812, Oct. 5, 1915.

In Patent No. 1,071,676, issued to me on August 26, 1913, there is disclosed a method for applying fibrous insulating material to conductors by winding a thread coated with fibers, such as asbestos, about the conductor, then impregnating the fibers with a suitable binding material, and reducing the insulating sheath thus formed to a smooth and uniform condition. This method of insulating conductors is readily carried out by means of the apparatus disclosed when the conductors are circular in cross-section, and the results obtained are wholly satisfactory, as a consequence of which asbestos-covered wire manufactured by this method has gone into successful and extended use.

I have found, however, that difficulties of a substantial nature are encountered when it is sought to correspondingly apply insulating material to conductors of the flat-wire type. The chief cause of difficulty arises by reason of the operation of the finishing mechanism which includes smoothing devices arranged to clamp the conductor between spring-pressed die members and to rotate about the conductor as a center to produce a smooth cylindrical surface on the insulating sheath. Obviously, finishing apparatus of the general nature described cannot, unmodified, be used to advantage when the conductors are of the flat-wire type, not only because of the difficulty of bringing the rubbing surfaces to bear with a uniform pressure on all portions of the opposite flat faces of the wire, but also because it is difficult to avoid twisting the flat strip to such an extent that the smoothing operation is interfered with and the wire hardened to a degree that will seriously interfere with subsequent handling and working, in addition

to impairing its value as an electrical conductor.

It is the object of my invention to provide an insulated flat-wire conductor having a fiber coating of uniform thickness and homogeneity and a means and method for producing the same. These ends are accomplished generally by a construction and arrangement of apparatus which provides for laterally supporting the wire alternately from opposite sides and smoothing the faces and edges of the wire at the points where it is supported.

I utilize for this purpose a series of backing and supporting members along the faces of which the conductor is advanced, so that one face of a given section of the conductor is in engagement with a backing and supporting member while the face of the conductor directly opposite the engaged face is free, and the other face of a different section is engaged by a backing and supporting member with the face directly opposite free. It will be seen that a certain smoothing action takes place longitudinally of the wire as the wire is drawn along the backing and smoothing members. The primary smoothing action is, however, provided by a series of spring-pressed wiping or smoothing members carried by rotatable fliers so operating as to draw the wiping members laterally across the exposed face and edges of the supported sections of wire. The number of wiping members employed corresponds to the number of backing and supporting members, so that each backing and supporting member supports a section of wire while the unengaged face is being smoothed by the corresponding wiping member.

In the accompanying drawings, which are intended to be illustrative of merely one of many ways in which the disclosed method may be accomplished, and from which wide departures in forms of apparatus may be made,

Fig. 1 is a view in side elevation and largely diagrammatic of a flat-wire insulating apparatus embodying the invention;

Fig. 2 is an enlarged transverse sectional view taken along the line 2—2 of Fig. 1;

Fig. 3 is a view taken from the left of Fig. 2; and

Fig. 4 is an enlarged view in perspective of one of the flat-wire supporting and back-

In Fig. 1 of the drawings, there is shown mechanism for smoothing and finishing insulating flat-wire in accordance with the invention. This mechanism consists of a reel 1 from which the flat-wire conductor 2 is fed through a central opening in a flier 3 that operates to wind an asbestos-fiber covered thread 4 from the spool 5 carried by the flier into spiral convolutions on the advancing conductor 2. A device for applying suitable binding material to the asbestos covering is also provided, and this takes the form of a receptacle 6 in which a roller 7 rotates to supply the liquid binding material from the receptacle to the conductor. Smoothing and finishing mechanism is indicated generally at 8 and consists of a framework 9 in which are mounted the smoothing fliers 10, each of which is provided with a central opening through which the wire is advanced for the finishing operation.

The special construction of the fliers 10, by which they are adapted to perform smoothing operations on the flat surfaces of the conductor, contemplates the use of wiping or smoothing members 11, one of which is pivotally mounted on each flier at a point near the periphery thereof with the free end 25 extended toward the central part of the flier and having a rounded smoothing portion, indicated generally at 12, adapted to trail across the edges and available faces of the conductor as the smoothing member is rotated about the conductor in the revolution 30 of the fliers.

In order to exert a steady influence on the wire and hold it from movement laterally under the action of the smoothing 35 members, backing and supporting members 13 are provided whose function it is to engage one face of the wire while the wiping members 11 are trailing transversely across and correspondingly smoothing the opposite face. The members 13 are held against rotation by being keyed at one end 14 into the transverse stationary partition members 15 in the main framework 9, but form bearings 40 at the other end 16 which project into depressions in the fliers 10 and about which the fliers 10 rotate. An intermediate portion 17 of the supporting member 10 is semi-circular in cross-section, and the flat face 18 thereof has the same width as that of the conductor so that the member will form 45 a backing support for the engaged section of conductor from one edge to the other of the flat face with which it is in contact.

It will be seen that, with the construction 50 and arrangement of mechanism shown, the trailing and rounded end 12 of the smoothing member 11 will be drawn across the edges and the exposed face of the wire 2 once in each revolution of the carrying flier 10, and will move across the rounded

surface of the backing member for one-half the distance traveled in each rotation. The function of the member 13 now becomes apparent in that it provides a backing support for preventing lateral movement of the wire as the spring-pressed smoothing member 11 performs its smoothing operation on the exposed face thereof. It will be seen also that, since the width of the supporting member is the same as the width of the insulated wire, the smoothing member 11 passes from the surface of the member 17 and across the edge of the wire without any interruption or shock that would tend to injure the insulating sheath on the comparatively thin edge of the conductor. It will be noted that any fibers that project outwardly from the edge of the wire will be engaged by the smoothing member and laid over against the adjacent flat face of the wire or along the adjoining curved surface of the member 17.

In order to dispose of the fibers left in the latter situation and to smooth and finish the surface of the opposite face of the wire, another supporting member is made use of and is so arranged as to engage the face of the wire opposite the face engaged by the supporting member just described, and at a point separated therefrom along the length 95 of the wire. Thus, it will be seen that successive sections of the wire are simultaneously operated upon, one face of one section being smoothed while the opposite face of the next adjoining section is having the smoothing 100 operation performed upon it. It will be evident that this operation can be extended to any desired limit merely by adding to the number of smoothing device units made use of in the series going to make up the 105 smoothing and finishing mechanism as a whole.

In Fig. 1 of the drawings, a series of four smoothing devices is shown, but it is to be understood that the particular number employed is capable of variation to suit the requirements of different grades of work. Each smoothing unit flier 10 is preferably independently driven through a gear train 19 from any desired source of power, 110 and it will be evident that the speed at which the fliers are driven is a factor in the effectiveness of the smoothing and finishing operation and can accordingly be controlled and regulated as desired.

The advancing of the wire along its axis is obviously productive of a smoothing action along the length of the wire brought about by the relative movement between the flat faces 18 of the supporting members 17 and the engaged surfaces of the wire. The advancing movement of the conductor through the mechanism results, not only in a helical winding of the asbestos covered cord 4 on the wire, but it also produces a 125 130

corresponding helical path of travel of the smoothing members 11 across the face and edges of the conductor so that the main smoothing action is in the direction of the 5 lay of the wound material. The effect of this is to thoroughly incorporate the asbestos fibers and the finishing material into an insulating sheath having a uniform thickness with correspondingly high dielectric 10 properties, and a homogeneity that is a requisite in a good insulator. As the finished wire is drawn from the smoothing and finishing mechanism at 20, it may be subjected to any further treatment desired, 15 such as spraying or heating, or wound directly on the receiving reel 21.

What I claim is—

1. An insulated flat wire finishing apparatus comprising a relatively stationary support arranged to engage one face of the wire and a smoothing device mounted for rotation about the axis of said support and wire and adapted to smooth the unengaged surface thereof.
2. An insulated flat wire finishing apparatus comprising a relatively stationary support for one face of the wire, a resilient smoothing device mounted for rotation about the axis of said support, means for advancing the wire and means for rotating said smoothing device.
3. An insulated flat wire finishing apparatus, comprising, supporting means ar-

ranged to engage one face of a section of the wire, means for transversely smoothing 35 the unengaged face and edges of the section, supporting means arranged to engage the opposite face of a different section of the wire, and means for transversely smoothing the unengaged face and edges of the last- 40 named section.

4. An apparatus for finishing covered flat wire, comprising, a supporting and smoothing member arranged to engage one face of a section of the wire, means for advancing 45 the wire to effect a longitudinal smoothing action of the engaged section, and means for transversely smoothing the opposite face and edges of the engaged section.

5. An apparatus for finishing covered flat 50 wire, comprising, a wire supporting member arranged to engage one of the faces of a section of wire, a wire supporting member arranged to engage the opposite face of a different section of the wire, means for advancing 55 the wire to effect a longitudinal smoothing action on the engaged sections, and means for transversely smoothing the free faces of the supported sections.

6. The method of finishing insulated flat- 60 wire conductors, which consists in longitudinally advancing the conductor and in alternately supporting and smoothing the opposite faces of successive sections of the wire.

JOHN ALLEN HEANY.
